JOHN M. KOCH, OF WYOMISSING, PENNSYLVANIA

AUTOMATIC DISCHARGE DEVICE FOR GRINDING MACHINES

Application filed March 3, 1931. Serial No. 519,749.

My invention relates to automatic discharging devices for grinders and has a particular reference to mechanisms adapted to automatically remove bars from a centerless grinding machine.

For the continuous operation of centerless grinding machines it is necessary to have workmen on one side of the machine to feed the raw rods, and other workmen on the other side to remove the finished bars or rods. In my copending application, Serial No. 435,820, filed Mar. 14, 1930, I described an automatic device for feeding rods into the grinding machine, and the present invention refers to an automatic take-out device intended to eliminate the manual labor for removing the finished rods.

The action of grinding wheels on the rod causes the latter to move longitudinally at a uniform rate of speed. The finished portion of the rod must move with as little friction as possible, preferably on rollers, and cannot be retarded or accelerated so as not to affect the accuracy of grinding. The take-out mechanism during this part of the process must be, therefore, inoperative.

At the time, however, when the end of the rod begins to leave the grinding wheel, the propelling action of the wheels ceases, and the rod must be positively pulled until it clears out the housing of the machine. For this purpose in my device rollers are brought under the rod and are turned by a suitable motor thereby moving the rod out of the machine. The rollers are then raised, when the tail end of the rod clears the machine housing, so as to throw the rod to one side of the take-out stand, into a waiting car or suitable receptacle. The rollers are provided with a flange on one side or with a taper so as to roll the rod to one side after it has cleared the guiding rollers.

The operation of the rollers are controlled by the movement of the rod by means of a suitable electric or pneumatic control.

My invention is more fully described in the accompanying specification and drawings in which—

Fig. 1 is an elevation of my device partly

in section, Fig. 2 is a section on the line 2—2, Fig. 1.

My device consists of rails 1 supported on threaded rods 2 with nuts 3 resting on top of tubular posts or standards 4. A number of horizontal rollers 5 in brackets 6 are supported in the slots between the rails 1. These guiding rollers are adapted to support rods 7 which are being ground between grinding wheels 8 located in a housing 9 of a centerless grinding machine. The position of the rails with rollers can be adjusted for rods of different thickness by turning the nuts 3.

Side brackets 10 are also supported on the rails 1 with side guiding rollers 11. The brackets are fastened with bolts 12 and are provided with slotted holes for them so that their position can be adjusted for rods 7 of different thickness.

A frame 13 is attached underneath the rails 1 supporting my take-out mechanism. It has a horizontal bar 14 with bearings 15 in which slide vertical rods 16 with brackets 17 on top. Shafts 18 of the rollers 19 are journaled in these brackets and are provided with worm gears 20 in mesh with worms 21 on a shaft 22. The brackets 17 have lugs 23 with bearings for the shaft 22. A sprocket 24 is mounted on the shaft 22 and is connected by a chain 25 with a sprocket 26 on the shaft of a motor 27 which is mounted on a bottom bar 28 of the frame 13.

The lower ends of the rods 16 rest on cams 29 mounted on a shaft 30 journaled in the bars 13. A gear 31 is mounted on this shaft and is in mesh with a pinion 32 on the shaft of the motor 27.

The cams have four different portions: portion or sector 33, concentric with the shaft 30; sector 34, eccentric to the shaft 30 and forming a transition to a sector 35 described of a larger radius and concentric with the shaft, and a sector 36 formed with an eccentric hump.

A second type of cam is mounted on the end of the shaft 30, with a large sector 37, and a small sector 38, adapted to operate the middle lever 39 of a two way switch having two stationary contact levers or arms 40 and 41. The switch is connected by a wire 42 with

the motor 27, and by wires 43 and 44—with a control switch arm 45 pivoted on a shaft 46 and adapted to be deflected by the rod 7. The free end of this arm operates the middle lever 47 of a control switch against the tension of a spring 48, located between stationary contact arms 49 and 50. A return wire 51 connects the switches with a source of electric current 52 and with the motor 27.

10 The operation of my device is as follows.

While the rod 7 is being ground in the machine, it keeps the lever 45 deflected, closing the contact points 47 and 50. The cams 29 and 37 remain in their inoperative position as shown with dotted lines at the right of Fig. 1 and in Fig. 2. The arm 39 is pressed by the spring 53 against the arm 41 so that the current is disconnected and the motor stands still, with the rollers 19 in their lowest position where they do not touch the bar 7. The latter rolls freely on the rollers 5 and 11 being pushed by the grinding wheels of the machine.

As soon as the rear end of the rod 7 reaches 25 the end of the grinding wheel 8, it slides from under the lever 45 which swings in its neutral vertical position as shown with dotted lines in Fig. 1, under action of the spring 48. The lever 47 leaves the contact 50 and engages the 30 contact point 49 thereby closing the circuit for the motor 27 which begins to turn. The cam 29 gradually lifts the rods 16 with the rollers 19 by its rising or eccentric portion 34. The rollers come under the rod 7 lifting 35 same from the rollers 5. The rotation of the rollers 19 will cause the rod 7 to move to the left and away from the machine. The speed of the motor and the gear ratios are so adjusted that the rear end of the rod 7 leaves 40 the housing 9 of the machine while the cams 29 still slide under the rods 16 by their concentric sectors 35.

At the time when the rear end of the rod 7 leaves the housing 9 of the machine, the 45 hump 36 of the cam 29 lifts the rollers 19 to their highest position as shown with dotted lines in Fig. 1 thereby bringing the rod 7 above the edge of the inclined shelves or slides 54 attached to brackets 10 with bolts 55. The 50 rollers or wheels 19 are tapered to the side on which the slides 54 are located thereby causing the rod 7 to roll off on the slides and into a receptacle (not shown) for finished rods.

The position of the slides 54 can be adjusted 55 to suit rods 7 of different thickness.

After throwing the rod 7 off the machine, the rolls 19 return to their lowest or inoperative position when the cams 29 turn so as to bring their low sectors 34 under the rods 16. 60 But if there is no new rod 7 coming from the grinding wheels 8 and deflecting the lever 47, the motor will automatically stop when the enlarged section 37 of the contact cam moves the arm 39 from the contact point 41 65 into engagement with the contact arm 40. As

soon as a new rod 7 engages the arm 45, the motor will start again and will operate, bringing down the rollers 19, until the low portion 38 of the contact cam comes against the arm 39 thereby permitting same to engage the 70 contact arm 41. The motor will then stop until the rear end of the new rod 7 leaves the contact lever 45.

Important advantages of my device are 75 that it provides means for automatically removing finished rods from the machine thereby eliminating the necessity to employ labor for this purpose. My device can be used with rods of any ordinary thickness and in any random length, the operation being controlled by one end of the rod only.

The rollers 19 can be made to be operated by air cylinders instead of an electric motor, the end of the rod 7 operating air valves.

The driving chain or belt 25 is kept tight 80 for all positions of the shaft 21 by an idler 56 on an arm 57 pivoted at 58 and kept under tension by a spring 59.

I claim as my invention:

1. In an automatic discharging device for 90 grinding machines, the combination with rails adapted to slidably support the work from a grinding machine, means to lift said work from said rails upon completion of the grinding operation, means to direct said work to one side of said rails, and means to control said lifting operation, said controlling means being adapted to be operated by the rear end of said work.

2. In an automatic discharging device for 100 grinding machines, the combination with rails adapted to slidably support the work in the form of rods from a grinding machine, means to positively pull said work from said machine when the grinding operation is completed, means to discharge said work from said rails when said work is pulled away from said machine, and means to control said pulling and said discharging means, said controlling means being adapted to be operated by said work.

3. In an automatic discharging device for 110 grinding machines, the combination with rails adapted to slidably support the work in the form of a rod coming from a grinding machine, adjustable guides for said work, rollers under said work, means to bring said rollers in contact with said rod and to rotate said rollers thereby pulling said rod away from said machine when the grinding operation is substantially completed, and means to control said pulling and said discharging operations, said controlling means being adapted to be operated by said rod.

4. In an automatic discharging device for 120 grinding machines, the combination with rails in coordination with said machine, adjustable guides for the work in the form of rods coming from said machine, said guides being supported on said rails, rollers adapted 125

to engage said work when the grinding operation is substantially completed, means to rotate said rollers thereby pulling said work away from said machine, and means to lift 5 and to discharge said work from said guides and from said rollers when said work is pulled away from said machine.

5. In an automatic discharging device for grinding machines, the combination with 10 rails adapted to slidably support the work coming from said machine, rollers adapted to engage said work from underneath when the grinding operation is substantially completed, means to rotate said rollers thereby 15 pulling said work away from said machine, means to raise said rollers when said work is pulled away from said machine, and means to guide said work by gravity from said rails.

6. In an automatic discharging device for 20 grinding machines, the combination with rails adapted to slidably support the work coming from a grinding machine, rollers under said rails, a motor adapted to rotate said rollers, means to bring said rollers in contact with said work thereby pulling said 25 work away from said machine when the grinding operation is practically completed, and means to discharge said work from said rails when the rear end of said work clears 30 the housing of said machine.

7. In an automatic discharging device for grinding machines, the combination with rails adapted to slidably support the work from a grinding machine, rollers under said 35 rails, a motor adapted to rotate said rollers, cams adapted to raise said rollers into engagement with said work when the grinding operation is practically completed thereby pulling said work away from said machine, 40 guides on said rails for said work, said cams being further adapted to lift said work above said guides when said work is pulled from the housing of said machine, and means to guide said work from its raised 45 position to roll by gravity to one side of said rails.

8. In an automatic discharging device for grinding machines, the combination with 50 rails adapted to slidably support the work coming from a grinding machine, rollers in a cooperative relation with said work, a motor adapted to rotate said rollers thereby pulling said work away from said machine, means to control the operation of said motor by 55 said work, means to raise said work by said motor above said rails, and means to guide said work from its raised position to one side of said rails.

9. In an automatic discharging device for 60 grinding machines, the combination with rails adapted to slidably support the work coming from a grinding machine, rollers in a cooperative relation with said work, a motor adapted to rotate said rollers thereby 65 pulling said work away from said machine,

a controlling device for said motor adapted to be operated by said work and adapted to render said rollers operative when the rear end of said work is ready to leave the grinding wheels of said machine, and means to 70 discharge said work from said rails when the rear end of said work clears the housing of said machine.

In testimony whereof I affix my signature.
